[57] **CLAIM**

The ornamental design for plumbing tool for a drain fixture, as shown and described.

DESCRIPTION

FIG. 1 is a perspective view of the invention, shown in relation to an exemplary drain fixture;
FIG. 2 is a second perspective view of the invention;
FIG. 3 is a side view of the invention;
FIG. 4 is a second side view of the invention, rotated 90° relative to the side view of FIG. 3;
FIG. 5 is a top view of the invention;
FIG. 6 is a bottom view of the invention; and.
FIG. 7 is a cross-sectional view of the invention taken along line 7—7 of FIG. 3, showing the relative depths of apertures formed in the top and bottom of the invention.
The broken line showing of a drain fixture is for illustrative purposes only and forms no part of the claimed design.
